UNITED STATES PATENT OFFICE.

CARL WICHT AND WILLIAM E. DIPPERT, OF DES MOINES, IOWA.

DESIGN FOR A LOOP-PLATE FOR TOP-COLLAR FASTENERS.

SPECIFICATION forming part of Design No. 32,279, dated February 27, 1900.

Application filed January 16, 1900. Serial No. 1,690. Term of patent 14 years.

To all whom it may concern:

Be it known that we, CARL WICHT and WILLIAM E. DIPPERT, citizens of the United States of America, and residents of Des Moines, Polk county, Iowa, have invented a new and useful Design for a Loop-Plate for a Top-Collar Fastener, of which the following is a specification.

The object of this invention is to provide a new, useful, and ornamental design for a loop-plate for top-collar fasteners; and our invention consists of the design hereinafter set forth, pointed out in our claim, and illustrated by the accompanying drawings, in which—

Figure 1 is a plan of the loop-plate embodying our design. Fig. 2 is a bottom view of the loop-plate shown in plan in Fig. 1. Fig. 3 is an edge view or elevation of the loop-plate. Fig. 4 is a longitudinal section of the loop-plate on the indicated line 4-4 of Fig. 1. Fig. 5 is an end view or elevation of the loop-plate.

In the design as shown the numeral 10 designates a loop-plate relatively thin in respect of its other dimensions and tapering as to thickness. An angularly-arched loop-bar 11

is located on and extends laterally at right angles from the thicker end portion of the plate 10 intermediate of the side margins of said plate. A hole or eye 12 of angular form 30 is provided in the thicker end portion of the plate 10 and between the bases of the laterally-extending portions of the loop-bar 11. An ear 13 extends laterally at right angles from one side margin of the convex face of 35 the plate 10, and the outer end portion of said ear is rounded.

The characteristic features of this design are the longitudinally-curved plate having the ear at right angles to one side margin 40 thereof, the eye or hole in one end portion of said plate, and the loop-bar arched above and crossing said eye or hole.

We claim as our invention—

The design for a loop-plate for a top-collar 45 fastener, substantially as herein shown and described.

CARL WICHT.
WILLIAM E. DIPPERT.
